UNITED STATES PATENT OFFICE.

SEWARD W. WILLIAMS, OF LAPEER, MICHIGAN.

FEED-REGULATING DEVICE FOR ELECTRIC MOTORS.

No. 796,483.

Specification of Letters Patent.

Patented Aug. 8, 1905.

Application filed June 1, 1903. Serial No. 159,459.

To all whom it may concern:

Be it known that I, SEWARD W. WILLIAMS, a citizen of the United States, residing at Lapeer, in the county of Lapeer, State of Michigan, have invented certain new and useful Improvements in Feed-Regulating Devices for Electric Motors; and I do declare the following to be a full, clear, and exact description of the invention, such as will enable others skilled in the art to which it appertains to make and use the same, reference being had to the accompanying drawings, and to the figures of reference marked thereon, which form a part of this specification.

This invention relates to a controller-feed-regulating device for electric motors especially designed for use on street-cars; and it consists in the construction and arrangement of parts hereinafter fully set forth, and pointed out particularly in the claims.

The objects of the invention are to provide simple and efficient means for regulating the controller-feed, so as to obviate overfeeding the motors, the arrangement being such as to prevent the feeding of more than one point at a time in ordinary running, compelling a slight pause between each point to enable the motor to properly take up the current, to provide for affording three points upon the reverse of the motor for emergency, to provide for locking the operative lever which regulates the feed of the current-controller when the car is not in use, and to provide for quickly throwing off the current by a single movement of the lever.

The above objects are attained by the structure illustrated in the accompanying drawings, in which—

Figure 1 is a side elevation of the controller-feed-regulating mechanism, part of the case in which part of said mechanism is located being removed, as well as one of the side plates of the operative lever, to show the position of the operative parts. Fig. 2 is an elevation with one of the outer plates only of the case removed. Fig. 3 is a plan view of the complete apparatus. Fig. 4 is a fragmentary view in detail, showing by dotted lines the movement of the locking and releasing dogs. Fig. 5 is a horizontal section as on line 5 5 of Fig. 1. Fig. 6 is a vertical section as on line 6 6 of Fig. 1. Fig. 7 is an enlarged detail in section of the parts which control the movement of the locking-plunger. Fig. 8 is a fragmentary view in elevation, showing the movable locking-pawl and the rack-segments

adapted to be engaged thereby. Fig. 9 is a fragmentary view in perspective of the device for locking the lever against movement. Fig. 10 is a transverse section through the parts of said lock, showing the key in engagement therewith.

Referring to the characters of reference, 1 designates the top of an ordinary controller-box in which is located the controller, by means of which the current is fed to the motor, which parts are of the ordinary construction and need not be described herein.

Instead of the ordinary rotatable handle by means of which the controller-staff is actuated to feed the current to the motor there is employed in this apparatus a beveled gear 2, fixed to the upper end of said staff 3 above the top of the controller-box.

Located upon the top 1 and secured by suitable screws 4, as shown, is a case 5, having a central partition 6, which divides the interior of the case and forms between its faces and the sides of the case open spaces, in which are located some of the operative parts, as herein-after stated. Journalized in the open space, between the partition 6 and the side plate 7 of the case, is a pinion 8, carrying a beveled gear-wheel 9, which meshes with the gear 2 on the controller-staff. Lying in the space between the plate 7 and the central partition 6 is a plate 10, carrying at its lower end the segmental rack 11, which meshes with the pinion 8. Said plate carrying said rack is pivoted at 12 within said case, and the upper portion 13 thereof extends onto and forms one side of the hollow operative lever 14, the other side of said lever being formed by the plate 15, whose lower end is pivoted at 16 to the opposite side of the case in transverse alinement with the pivotal point 12 of the plate 10.

Formed upon the upper edge of the central partition 6 is an upwardly-projecting semicircular portion 17, and upon the upper edge of the side plate 18 of the case is an upwardly-projecting semicircular portion 19, which exactly registers with the semicircular portion 17, above described. Formed in the edge of each of these semicircular portions are the notches 20 and 21, which will correspond with the indicating points of contact on the controller. Pivoted at 22 between said notched semicircular portions is a downwardly-dependant arm 23, having at its upper end a rack-segment 24. Fixed to the semicircular portion 19, adjacent the rack-segment 24, is a rack-segment 25, having the notches 26 adjacent the notches of the

rack-segment 24 and the notches 27 spaced therefrom. The lower end of the arm 23 depends within the case and is supported normally upon the stem 28, projecting from the reversing-staff 29, adapted to be actuated through the handle 30. When the arm 23 is held up by the stem of the reversing-staff, the notches 31 of the segment 24 stand in a plane concentric with the notches 26 and 27 on the fixed segment 25, which is the normal position when running and the purpose of which arrangement will be hereinafter explained.

Mounted upon the outer face of the lever 14 is a reciprocatory plate 32, which is confined to move in a way formed by the inwardly-projecting flanges 33 on said lever. Extending laterally from the plate 32 is an ear 34, through which passes the lower threaded end of the rod 35, said rod having upon each side of said lever a threaded nut 36. The upper end of the rod 35 passes through a guide 37 and is pivoted to the small lever 38, which is in turn pivoted at 39 to the main lever. By a movement of the lever 38 the rod 35 is actuated to raise the plate 32 to free it from the notches in the semicircular portions 17 and 19, with which it is adapted to normally engage, said plate being held in engagement with said notches by means of the coiled spring 40, which is mounted upon the rod 35 and is compressed between a collar thereon and the guide 37, through which said rod passes.

In the normal position of the parts a forward movement of the main lever 14 would cause the plate 32 to engage the first notch of the series 20 which it encountered and prevent a further movement of said lever until said plate had been raised by an operation of the small lever 38. To prevent the main lever from being moved ahead farther than the distance of one notch when the plate 22 is raised past the first notch encountered, a reciprocatory plunger 41 is employed, which is located vertically within the main lever, its lower end passing freely through a guide 42, as clearly shown in Fig. 7, and extending normally into the plane of the notches on the fixed and movable segments 24 and 25. Attached to said plunger near its lower end is a coiled spring 43, which is adapted to draw the lower end of said plunger forward when released from one notch, so as to insure its engagement with the succeeding notch. The upper end of said plunger is provided with a loop or oblong eye 44, which extends above the upper guide 45, through which said plunger passes through said eye and is supported in suitable guides 47. Upon the plunger 41 is the coiled spring 48, which is attached at one end to a collar on said plunger and at the other end to the upper guide 45. The tension of said spring is normally exerted to hold the plunger in a raised position. Pivoted to the slide 46 is a lever 47^a, which is fulcrumed at 49 near its longi-

tudinal center and is pivoted at its upper end to the rod 50, which is in turn pivoted to the small lever 38. By a movement of the small lever 38 near its fulcrum toward the large lever 14 the lever 47, attached to the slide 46, will actuate said slide to retract it through the loop or eye in the plunger, allowing the spring 48 to force the plunger 41 downward as the reduced or wedge-shaped end of the slide is drawn through said eye, thereby presenting the lower end of said plunger in the path of the teeth 31 and 26 upon the rack-segments 24 and 25, thereby arresting a further movement of the main lever 14 upon its pivot while the small lever 38 is held in engagement, with the handle of the main lever, as shown by dotted lines in Fig. 4. It will be noted that this movement of the small lever 38 which withdraws the slide from the loop of the plunger 41 simultaneously raises the plate 32 from engagement with the teeth 20 of the circular racks 17 and 19. By this arrangement the main lever is allowed to be operated a notch at a time. These notches correspond with the points of contact in the controller, thereby preventing the current from being fed to the motor except intermittently and only a point at a time under ordinary conditions.

With the parts in the position shown in Fig. 1, in which position the current is entirely cut off from the motor by the controller, should the motorman desire to start his car he presses the small lever 38 against the handle of the main lever 14 and shoves the main lever forward until it is arrested by the plunger 41, which engages the first notch 31 of the segmental rack 34, which movement actuates the controller-staff to bring into service one point of contact therein. Before the main lever can be moved farther to place an additional point in service the small lever 38 must be released, when the force of the spring 40 will move the plate 32 downwardly into engagement with the teeth 20 of the semicircular racks 17 and 19, thereby locking the main lever from movement and withdrawing by the same operation the plunger 41 from the first notch 31 of the segment 24, past which it is caused to slip as it is freed therefrom by the action of the spring 43. By again moving the small lever 38 forward against the handle of the main lever the plate 32 will be raised so as to free it from the notches 20, allowing the main lever to be moved forward another notch until the plunger 41 encounters the second notch in the segment 24, thereby actuating the controller-staff to place two points in service, and so the operation continues by alternately moving the small lever forward against the handle of the main lever and releasing it. The main lever may be moved forward a notch at a time, thereby actuating the controller to feed the current to the motor a point at a time. This

small lever may be actuated quickly, so that the pause in the movement of the main lever need not be of great duration; but said pause is sufficient to enable the motor to take up the current as it is fed and prevent the current being fed to the motor faster than it can be utilized, thereby obviating the burning out of the motors, as often happens.

The first series of teeth of notches in the semicircular racks 17 and 19, as well as in the segmental racks 24 and 25, control the feeding of the current to the first motor. The second series of teeth in said racks and segments control the feeding of the current to the second motor. The interposed space between said teeth corresponds to the loop connecting the motors.

The movement of the main lever which controls the feeding of the current to the motor a point at a time is illustrated by dotted lines in Fig. 4, wherein is shown the operation of the detent-plate 32 and the plunger 41, whereby said parts are actuated simultaneously to alternately engage the notches of their respective racks and allow the intermittent movement of the main lever a notch at a time in the feeding of the current. The arrangement of the parts is such that the main lever cannot be actuated to place more than one point at a time of the controller in service, owing to the fact that as the detent-plate 32 is raised from the notches 20 the plunger 40 is projected into the path of the succeeding notch in the segmental racks 24 and 25, and when said plunger is withdrawn from engagement with said notches said plate is again depressed so as to engage the succeeding notch 20 of the racks, thereby preventing excessive feeding of the current to the motor and compelling a slight pause after each additional point is brought into service.

Electric-motor controllers of this character are provided with a reversing-switch actuated through the medium of a shaft or staff 29. The reversing-switch is brought into requisition when it is desired to reverse the motor for an emergency stop or when it is desired to run the car backward. As before stated, the normal position of the stem 28, which projects from the reversing-staff 29, causes the free end thereof to lie within the slot 51 in the case under the arm 23, so as to cause the notches of the segment 24 to stand in a plane concentric with the notches 26 and 27 on the fixed segment 25. When the handle 30, however, is actuated to operate the reversing-switch, it is moved to the position shown by dotted lines in Fig. 3, thereby swinging the stem horizontally of the slot 51 and withdrawing it from the support of the arm 23, when the spring 52, attached to said arm, will swing its free end downwardly upon the fulcrum or pivot 22 and cause the notches 31 thereof to drop below the plane of and stand eccentric to the notches 26 and 27 of the fixed

segment, as shown by dotted lines in Fig. 1, in which position a movement of the main lever 14 to feed the current to the motor through the operation of the controller-staff will cause the plunger 41 to pass the notch 31 of the segment carried by the arm 23 and engage the third notch or the first of the notches 26, thereby giving the motor three points at once in case of emergency. When using the reverse-switch in the ordinary movement of the car about the yard, the emergency three points are not necessary, and therefore provision is made for locking the arm 23 in its normal position by passing a key or pin 53 through the side of the case and into said arm, as clearly shown in Fig. 6, whereby the movement of the stem 28 on the reversing-staff does not effect the position of said arm, so that the segment 24 remains unchanged in its position upon the reversing of the controller, and the motor-man is unable to feed the current to the motor faster than a point at a time with the car moving in either direction.

To prevent tampering with the controller and a possible injury thereto and to the operative lever when the car is not in service, provision is made for locking the main lever through the medium of a gravity-dog 54. (Shown more clearly in Fig. 9.) This dog is pivotally mounted within the main lever and is adapted by gravity to drop downwardly into the notches 20 of the rack 19, as shown by dotted lines in said figure, whereby the main lever becomes locked against movement, and the controller-staff is thereby held from turning. For the purpose of holding the dog raised from said notches when the main lever is in use there is employed a tripping-finger 55, which is pivoted upon a shaft 56, mounted in the frame 57 within the main lever. Upon the shaft of said finger is a coiled spring whose tension is exerted to prevent a movement of the finger except when operated by the key 58. Projecting from one end of the dog 54 is a lateral portion 59, which extends into the path of the tripping-finger 55, so that when said finger is turned to stand in the position shown in Fig. 9 it engages the dog and raises it from the notches 20. One end of the shaft 56 is squared to receive the key 58, by means of which said shaft may be turned to release the dog by carrying the finger 55 away therefrom, allowing said dog to drop into the notches 20 and lock the lever, as before described.

When moving the lever to feed the current to the motor or motors, after the first motor has been put in service the second motor is cut in by moving the lever still farther over until all the points or notches of the second series are placed in service. This movement of the lever is such as to cause the controller-staff to make nearly a complete revolution and is equal to one full turn of the handle which is ordinarily employed upon the con-

troller-staff. When it is desired to cut off the current, it is only necessary to grasp the main lever and draw it quickly backward to the initial position, when the controller-staff will be rotated back to the initial or starting point, so that the indicator will rest at naught, showing that the current is entirely off the motor.

Having thus fully set forth my invention, what I claim as new, and desire to secure by Letters Patent, is—

1. In a feed-regulating device for electric-motor controllers, the combination with the controller-staff, of a gear mounted thereon, means connected with said gear for imparting a rotation thereto, a pivoted lever independent of the staff for controlling said gear-actuating means, said lever being capable of an intermittent movement only in one direction, whereby an intermittent rotation is imparted to the controller-staff.

2. In a feed-regulator for electric-motor controllers, the combination with the controller-staff, of a gear mounted thereon, a lever carrying a segmental rack which is connected with said gear, means connected with said lever for allowing an intermittent movement only in one direction and for permitting a continuous movement thereof in the opposite direction.

3. In a feed-regulator for electric-motor controllers, the combination with the controller-staff, of a beveled pinion thereon, a beveled gear engaging said pinion, and carrying a spur-gear, a semicircular rack engaging said spur-gear, a pivoted lever to which said rack is secured, whereby by a movement of said lever, said gears are rotated to rotate the pinion on the controller-staff, a circular rack having teeth thereon, and a movable detent-plate carried by the lever adapted to engage said teeth.

4. In a feed-regulator for electric-motor controllers, the combination with the controller-staff, of a gear on said staff, the main lever pivotally mounted independently of the staff adapted to actuate said gear to rotate said staff by a movement of said lever, an auxiliary lever mounted upon the main lever, mechanism connected with said auxiliary lever to regulate the motion of the main lever so as to permit only a limited intermittent movement

thereof when actuated to feed the current to the motor.

5. In a feed-regulator for electric-motor controllers, the combination with the controller-staff, of a pivoted lever connected therewith to rotate said staff by a movement of the lever upon its fulcrum, a circular rack adjacent said lever, a reciprocatory locking-plate adapted to engage the teeth of said rack, a second rack and a reciprocatory plunger adapted to engage the teeth thereof, and means for actuating the plunger and the locking-plate simultaneously to cause them to alternately engage with and disengage from the teeth of their respective racks.

6. In a feed-regulator for electric-motor controllers, the combination with the controller-staff, of a lever connected to and adapted to rotate said staff, a reciprocatory plunger in said lever, a pivoted rack having teeth extending into the path of said plunger, an arm connected with said rack, a reversing-staff, a stem on said reversing-staff extending into engagement with said arm, whereby the teeth of the segment are normally held in the path of said plunger but are caused to fall below the path of said plunger by movement to reverse the motor.

7. In a feed-regulator for electric-motor controllers, the combination with the controller-staff, of the lever connected with said staff to rotate it, means for preventing a movement of said lever, except intermittently, a reverse-staff, means actuated by a movement of the reverse-staff for affording three points of contact in the controller upon the reverse thereof.

8. In a feed-regulator for electric-motor controllers, the combination with the controller-staff, of a pivoted lever adapted to actuate said staff by a movement of said lever upon its pivot, means interposed between the lever and staff for transmitting motion from the former to the latter and means independent of the staff-actuating means for locking said lever against movement when the car is not in service.

In testimony whereof I sign this specification in the presence of two witnesses.

SEWARD W. WILLIAMS.
